PISTON

Auguste Corthals, Ixelles-Brussels, Belgium

Application March 11, 1936, Serial No. 68,249
In Belgium March 13, 1935

1 Claim. (Cl. 309—11)

The present invention relates to a piston for internal combustion engines, explosion motors and other like engines in which the heat absorbed by the piston and the cylinder produces 5 a relatively considerable expansion of these elements.

It is known that the provision of the piston pin bosses produces an unequal distribution of the heat in the skirt of the piston and consequently 10 causes unequal expansions of the latter from one point to another in one and the same circular section.

For the purpose of eliminating this drawback, it has been proposed to use a yielding piston, 15 which affords a more considerable capacity of deformation in determined directions. This piston presents the drawback, owing to its lack of rigidity, to become deformed in an excessive and unadmissible manner at the moment when it produces the driving effort upon the connecting rod. 20 The deformations produced in this manner cause an important friction of the piston in the corresponding cylinder.

It has also been proposed to use semi-rigid pistons, by means of which the drawbacks of the 25 yielding pistons were reduced. These pistons present, in a reduced manner, the drawback of the rigid pistons consisting in a lack of capacity to follow the deformations of the cylinders. This 30 latter drawback also remains with unsymmetrical rigid pistons, which present the advantage of securing a better distribution of heat.

With these different types of pistons, it is moreover necessary to provide supplementary play 35 according to determined diameters.

Finally, it has been proposed to make the skirt yielding and to make it integral with the head, independently of the piston pin bosses which 40 were rigidly connected to the head by strong webs, independent of the skirt and attached to the head towards the middle portion thereof.

In the pistons of this type, the skirt is separated from the pin bosses by a groove which encircles entirely or partially these bosses.

45 By the fact that the central portion of the head has a higher temperature than the edges, said bosses become more heated than if they were integral with the head by means of the skirt. Moreover, they cannot eliminate the complete 50 portion of the heat they contain by conduction towards the skirt, because they are completely or partially separated from the latter. It results therefrom that their temperature is much higher than in the other known pistons. By this 55 fact, the difference between their expansion and

that of the piston pin is greater and a play is produced between these elements when the motor becomes heated. The repeated knockings which are produced in these conditions between these elements cause, after a certain delay, the 5 rupture of the pin bosses. The pistons of this latter type also present the drawback of necessitating different chill moulds for each spacing between the pin bosses.

The present invention has for its object to retain the advantages resulting from the use of a yielding skirt independent of the said bearings, while not presenting the drawbacks of the last mentioned type of pistons.

For this purpose, the yielding skirt is constructed so as to be also deformable in the direction of all its diameters.

The invention will be described hereafter with reference to the accompanying drawing.

Fig. 1 is a perspective view, partially broken, 20 of the embodiment of a piston according to the invention having four longitudinal slots;

Fig. 2 is a partial longitudinal section of this piston at right angles to the axis of the piston pin 25 bosses;

Fig. 3 is a transverse section through the skirt of a piston having eight longitudinal slots;

Fig. 4 is a longitudinal section through the piston of Fig. 2, passing through the axis of the pin 30 bosses.

In these figures, the same reference characters designate identical elements.

The piston illustrated in Figs. 1 to 4 comprises a head 2, to which are rigidly connected the piston pin bosses 3, by means of webs 4, said bosses 35 being also united to that part of the skirt in which are provided the grooves 13 for lodging the piston rings.

Except for the head side, the bosses 3 are separated from the skirt 5 by a slot 6 cutting completely the thickness of the skirt.

The piston skirt according to the invention is so constructed that it can also be deformed in the direction of all its diameters. It is formed with four parts 5a, 5b, 5d, 5f, yieldingly united to each other by inner yielding ribs 7. These ribs are arranged approximately at the angles of a square 8, shown in dotted lines in Fig. 1. Two sides of this square are almost parallel to the axis of the bosses 3.

The parts 5a, 5b, 5d, 5f, which have thus almost the same width, are separated from each other by slots 9, 10, 11 and 12. These slots are cut in the ribs 7 according to planes which are not radial planes. Two of these planes, for in- 55

stance the planes of the slots 9 and 11, are directed almost parallel to the side 8a, parallel to the axis of the bosses 3. The two other planes, those of the slots 10 and 12, are directed almost parallel to the side 8b, at right angles to the axis of the bosses 3.

As it may be seen on examination of Fig. 1, the slots arranged at the diametrically opposed angles of the square are directed parallel to the same side thereof.

The depth of the slots 9 to 12 is such that, assuming that the inner ribs 7 extend almost over the length of the parts 5a, 5b, 5d, 5f and are of the same composition as the latter, the remaining thickness of these ribs at the bottom of the slots be less than the thickness of said parts. In this way, the ribs 7 are more yielding than the parts mentioned. Ribs presenting such yield combined with the provision of slots in planes different from the radial planes constitute an important characteristic of the invention. Owing to this, the skirt is made perfectly yielding in all directions and fits conveniently the shape of the cylinder containing the skirt.

The slots 9, 10, 11 and 12 could be directed parallel to the generating lines of the cylindrical surface of the skirt, but they are preferably directed in a known manner somewhat obliquely with relation to these generating lines, so as to scrape the oil covering the inner surface of the cylinder.

It is to be noticed that for producing a per-

fectly yielding skirt, it is required that the parts mentioned be at least four in number.

In Fig. 3 has been illustrated a transverse section through the skirt of a piston which is furthermore divided by a set of four supplementary slots 14, 15, 16, 17 of similar arrangement to that of the slots 9, 10, 11 and 12 but offset with respect to this first set at an angle of substantially 45°. This skirt thus comprises eight parts almost of the same width.

Whatever may be the form of embodiment used, the inner yielding ribs, which are known per se, may be continuous or interrupted and formed from the same material as that which constitutes the parts they connect, or from a material different from that of these parts. Use could namely be made, in the case of a skirt in aluminium, of inner yielding ribs of Invar or steel.

I claim:

In a piston for internal combustion engines having a head, a skirt, piston pin bosses on the skirt and webs uniting the pin bosses to the head, a circumferential slot partially separating the pin bosses from the skirt except at the side between the bosses and the head, and longitudinal slots cut in ribs projecting inwards from the skirt, the arrangement whereby all the slots, viewed in transverse section of the piston, are approximately tangent to a circle concentrically located inside the piston skirt.

AUGUSTE CORTHALS.
